UNITED STATES PATENT OFFICE.

HOWARD D. COLMAN, OF ROCKFORD, ILLINOIS, ASSIGNOR TO HOWARD D. COLMAN,
LUTHER L. MILLER, AND HARRY A. SEVERSON, COPARTNERS DOING BUSINESS AT
ROCKFORD, ILLINOIS, AS BARBER-COLMAN COMPANY.

WARP-END-SUPPORTING MEANS.

1,069,082.

Specification of Letters Patent.

Patented July 29, 1913.

Application filed September 2, 1911. Serial No. 647,359.

To all whom it may concern:

Be it known that I, HOWARD D. COLMAN, a citizen of the United States, residing at Rockford, in the county of Winnebago and 5 State of Illinois, have invented certain new and useful Improvements in Warp-End-Supporting Means, of which the following is a specification.

In application Serial No. 507,233, filed 10 July 12, 1909, there is shown a warp-tying apparatus comprising means for supporting one end of the new warp and an end of the old warp while said warps are being secured in the clamps of the warp-uniting machine. 15 Said warp-end supporting means comprises two pivoted arms arranged to support a thread-holder consisting of a bar covered with card cloth or similar material. The bar is arranged to be removably placed 20 upon said arms at two different heights to correspond with the different horizontal planes of the warps. After the new warp has been secured in place the operator places 25 said bar in its upper position for use in securing the old warp in place in the machine.

The object of this invention is to improve said warp-end supporting means by obviating the necessity of transferring the thread-engaging bar from one place to another 30 upon the arms; to provide means, whereby, when the arms are swung downward, their pivotal support will also move downward automatically so as to be in position for use with the next warp or warp-section; to 35 facilitate the removal of the threads from the thread-engaging bar; and in other ways to lessen the amount of attention and effort required of the operator in the use of said warp-end supporting means.

40 In the accompanying drawings, Figure 1 is a fragmental vertical transverse section through a warp-tying machine embodying the features of my invention, the warp-end supporting means being shown as supporting one end of the upper warp. Fig. 2 is a 45 similar view showing the warp-end supporting means as supporting one end of the lower warp. Fig. 3 shows the supporting means in its withdrawn or inoperative position. Fig. 4 is a view upon a larger scale 50 showing the means for locking the support in its upper position, the means for locking the arms in their upper position, the means for releasing the first mentioned lock, and

the means for cushioning downward movement of the support. Fig. 5 is a section on line 5 of Fig. 3. Fig. 6 is a fragmental side elevation showing the parts in the position indicated in Fig. 3. Fig. 7 is an end view of the bar that supports the card cloth. 55

1 indicates the bed of the warp-tying machine. A clamp 2 is supported above said bed at one side thereof by means of a suitable number of posts 3. At the other side of said bed is a clamp 4 pivotally supported 60 by means of a rock shaft 5 carried by posts 3^a so that tension may be placed upon a warp held in the clamps 2 and 4.

6 refers to the frame in which the old warp is supported, said frame being provided with a fixed clamp 7 and a pivoted clamp 8. The threads are inserted into the clamps 2, 4, 7 and 8 by means of insertion bars 9.

The new warp *a* is wound upon a loom 75 beam which may be located in the loom or in a supporting framework of any suitable character. The old warp *b* likewise may extend from the loom or be supported at one end in any suitable manner. The opposite 80 end of the old warp and the corresponding end of the new warp are supported prior to and while the warps are being secured in the clamps 4 and 8 by the means to be now described. 85

To the bed of the machine at the side on which the clamps 4 and 8 are located I attach two brackets 10 each provided with perforated ears 11 and 12 providing bearings for a vertically slidable rod 13. Said rods 90 are rigidly secured together by means of collars 14 and a cross-bar or tie-rod 15, the vertical rods 13, collars 14 and horizontal rod 15 thus constituting a rigid vertically 95 slidable structure hereinafter termed the arm-supporting structure. Said structure is arranged to be locked in its upper position by means of two dogs 16 fixed upon a rock shaft 17 journaled in bearings on the collars 14, said dogs being arranged to enter recesses 18 in the brackets 10. A torsion spring 19 tends to rock the shaft 17 in the direction to place the dogs in locking position. Downward movement of the arm-supporting structure may be cushioned in any 105 suitable way as by means of coiled springs 20.

Two arms 21 rigidly secured together by means of a transverse rod 22 are pivoted

upon the rod 15 and are given a tendency to swing forwardly and downwardly by a torsion spring 23. Said arms may be locked against such movement by means of two dogs 24 fixed upon the ends of a rock shaft 5 supported by the arms 21, each of said dogs being arranged to engage in a notch 26 formed in a lug 27 cast integral with or otherwise suitably secured to each collar 14. A torsion spring 28 tends to rock the shaft 10 25 in the direction to place the dogs 24 in operative position.

29 is a hand lever for rocking the shaft 25 to throw out the dogs 24.

15 An arcuate projection 30 is formed upon each arm 21 in position to engage an arm 31 rigid with the adjacent dog 16, for automatically moving said dog out of the recess 18 when the arm 21 swings downward.

20 To the free end of each arm 21 is pivoted a bracket 32, and to these brackets is secured a bar 33 upon which is mounted card cloth or any other suitable material or devices for holding warp threads. As will be seen from the drawings, the pivots 34 of the brackets 25 32 are located so that when the arms are in their operative position the bar 33 may be swung up and toward the warp-tying machine by the operator. The card cloth 35 30 may be secured to the bar 33 in any suitable manner. Herein I have shown clips 36 in channel form which clamp the edges of the cloth to the bar 33, the latter being attached to the brackets 32 by screws 37. The 35 ends of the strip of card cloth are held to the bar 33 by clips 38.

40 The warp-tying machine may be made of sufficient capacity to operate upon the entire width of the warps at one time, or it may be designed to operate upon a section only of the warps at a time.

45 Assuming the parts of the apparatus to be in the position shown in Fig. 2 the operation is as follows: The new warp or a section thereof is laid across the clamps 2 and 4, and if the end of the warp has been tied into a loose knot, the operator unties said knot, and, taking a number of threads in one hand, he brushes them into substantial 50 parallelism by means of a brush, and secures the brushed-out ends by pressing them down upon the card cloth 34. This operation he repeats until there has been formed a sheet of substantially parallel threads extending over the clamps 2 and 4 to the bar 33. The sheet of threads is next secured in the clamps 2 and 4 by pressing insertion bars 9 against said sheet and into the clamps. The slack necessary to enable the sheet to 55 enter the clamp 4 is obtained through the tilting rearwardly of the arms 21, such tilting permitting the bar 33 to move nearer the clamp 4. After the clamps 2 and 4 have been closed, so as to securely hold the sheet 60 of threads, the operator swings the bar 33

upwardly and rearwardly on the pivots 34 and pulls the card cloth from the threads by pulling forwardly on the bar 33. The operator then lifts the arm-supporting structure into the position shown in Fig. 1 and 70 secures the old warp in the warp-tying machine in substantially the same manner as in the case of the new warp. The dotted line b' represents the position of the old warp after being brushed out and before 75 the warp frame 6 is placed thereon, the bar 33 moving from its dotted-line to its full-line position when the frame 6 is placed on the warp and the insertion bar 9 pushed into the clamp 8. After stripping the ends 80 of the old warp-threads from the card cloth, the operator operates the lever 29 to throw out the dogs 24, whereupon gravity and spring 23 cause the arms 21 to swing forwardly and downwardly. During such 85 swinging movement of the arms 21 the projections 30 engage the arms 31 of the dogs 16 and move said dogs out of the recesses 18, whereupon the arm-supporting structure drops onto the cushioning springs 20. 90 Said structure is then at the horizontal level requisite for the next operation, and the arms 21 are out of the way of the operating crank of the warp-tying machine.

95 While I have described the present embodiment and its uses with considerable particularity, I desire it understood that the invention is not limited to the details and uses herein set forth.

I claim as my invention:

1. The combination of two warp clamps, an auxiliary thread-holder, and a support for said thread-holder movable to place the thread-holder in operative relation to either of said clamps. 100
2. The combination of an upper and a lower warp clamp, an auxiliary thread-holder, and a vertically movable support upon which the thread-holder is supported. 105
3. The combination of an upper and a lower clamp, an auxiliary thread-holder, and a vertically movable support upon which the thread holder is pivotally supported for movement toward and away from the clamps. 110
4. The combination of an upper and a lower clamp, an auxiliary thread-holder, a vertically movable support upon which the thread-holder is pivotally supported, and means for locking the thread-holder against pivotal movement in one direction. 115
5. The combination with two clamps into which sheets of threads are to be inserted, of an auxiliary thread-holder yieldable toward the clamps to furnish the necessary slack in the threads, and a support for said thread-holder movable to place the thread-holder in operative relation to either of said clamps. 125
6. The combination of an upper and a 130

lower warp clamp, a vertically movable structure, thread-holding means pivoted on said structure, means for locking said structure in operative relation to the upper clamp, 5 and means for releasing said lock upon pivotal movement of the thread-holding means in one direction.

7. The combination of an upper and a lower warp clamp, a vertically movable structure, an arm pivoted on said structure, 10 thread-holding means carried by said arm, and means for locking said arm against downward pivotal movement.

8. The combination of an upper and a lower warp clamp, a vertically movable structure, an arm pivoted upon said structure, thread-holding means carried by said arm, a locking portion on said structure, 15 a dog carried by said arm and adapted to engage said portion to limit pivotal movement away from the clamps, and means tending to move said arm away from the warp clamps.

9. The combination of a warp-tying machine provided with an upper and a lower clamp, brackets fixed to said warp-tying machine below said clamps, a structure slidably supported by said brackets for vertical movement, two arms pivotally connected at 20 one end to said structure and rigidly con-

nected together, thread-holding means carried by the free ends of said arms, means tending to swing said arms away from the clamps, a dog on one of said arms and co-operating means on said structure for limiting such movement of the arms, a spring tending to hold said dog in operative position, means for releasing said dog, a dog on 35 said structure and coöperating means on one of said brackets for supporting said structure in its upper position, and a projection on one of said arms arranged to operate the last mentioned dog to withdraw it from operative position when said arms swing downwardly away from the warp clamps. 40

10. The combination of a warp clamp, means tending to move away from said warp clamp, and a thread-holder pivoted to said means.

11. The combination of a warp clamp, a 45 pivotally supported arm tending to move away from said clamp, and a thread-holder pivoted to said arm to swing upwardly toward the warp clamp.

In testimony whereof I hereby affix my 50 signature in the presence of two witnesses.

HOWARD D. COLMAN.
